LEROY H. SMITH AND FREDRICK L. CRASS, OF ITHACA, NEW YORK,
ASSIGNORS TO ITHACA GUN CO., OF SAME PLACE.

EJECTOR MECHANISM FOR BREECH-LOADING FIREARMS.

SPECIFICATION forming part of Letters Patent No. 593,616, dated November 16, 1897.

Application filed September 12, 1896. Serial No. 605,619. (No model.)

To all whom it may concern:

Be it known that we, LEROY H. SMITH and FREDRICK L. CRASS, of Ithaca, in the county of Tompkins, in the State of New York, have 5 invented new and useful Improvements in Breech-Loading Firearms, of which the following, taken in connection with the accompanying drawings, is a full, clear, and exact description.

10 Our invention relates to improvements in breech-loading firearms, and has for its object the production of a simple and practical device for ejecting discharged cartridge-shells; and to this end it consists, essentially, 15 in the construction and arrangement of the component parts of the firearm, all as herein-after fully described, and pointed out in the claims.

In describing this invention reference is 20 had to the accompanying drawings, forming a part of this specification, in which like letters indicate corresponding parts in all the views.

Figures 1, 2, and 3 are longitudinal vertical sections, partly in elevation, of portions of a firearm constructed in accordance with our invention, the ejector being shown in its operative position at Fig. 2 and the barrel being illustrated as dropped at Fig. 3; and 30 Figs. 4 and 5 are longitudinal vertical sections, partly in elevation, of portions of modified constructions of our improved firearm.

A represents the frame, B the barrel, and C the hammer, of this improved firearm, all 35 of which parts may be of any desirable form, size, and construction.

The frame A is provided with a front extension or arm a, having an upwardly-extending engaging face or shoulder a' at its forward extremity, and the barrel B is provided with a similar face or shoulder b, which is arranged at the rear of the face or shoulder a and is preferably formed upon a separable piece B', removably secured to the barrel B 45 by suitable fastening means B². The face or shoulder b is preferably arranged at substantially right angles with the barrel B, and the piece B' is usually provided with an upwardly curved or inclined face b', which extends rearwardly from said face or shoulder and forces

downwardly the rear arm of the ejector, presently described, as the barrel is raised.

The barrel B supports the extractor D and is provided with a suitable lug B³, which carries the ejector E. The extractor D is of any 55 desirable construction and is provided with a forwardly-extending rod d, and the ejector E preferably consists of a spring arranged to be compressed by the dropping of the barrel and to actuate the extractor to discharge the 60 cartridge-shell. The ejector E is usually arranged loosely within a slot or cavity in the barrel-lug B³ and is formed with separated upwardly-diverging arms e e' at its upper end. Directly beneath the lower end of the ejector 65 is an arm or projection b² on the barrel-lug B³, which prevents undue downward movement of the ejector as the same is forced downwardly by the engagement of its rear arm with the face b' of the piece B'. The 70 front arm e of the ejector engages the face or shoulder a' and a forwardly-inclined face b³, Figs. 1, 2, and 3, formed on the barrel-lug B³, and the rear arm e' engages the front end of the extractor-rod d and is movable into 75 and out of engagement with the face or shoulder b. As the barrels assume their normal position after their dropping the front end of the extractor-rod d engages the rear arm e' and forces the same toward the front arm 80 e, thereby tensioning said arms e e'.

F is a detent which is usually pivoted to the barrel-lug B³ and normally engages a shoulder e² upon the lower end of the ejector for holding the rear arm e' of said ejector 85 out of engagement with the face or shoulder b. A spring f operates to normally force the detent into operative position, and a trip or connection G is interposed between the mainspring C' for the hammer C and the detent F for forcing said detent from its operative position against the action of the spring f. The upwardly-diverging arms e e' of the ejector E are normally more or less tensioned, as previously stated, and constantly tend to 95 separate and move upwardly from between the front end of the extractor-rod d and the face b³, and when the detent F is forced from operative position the rear arm e' of the ejector automatically moves upwardly into engage- 100

ment with the face or shoulder b . The trip or connection G preferably consists of a rocking lever having its central portion fulcrumed beneath the front end of the mainspring C', its front end provided with a shoulder g , movable into engagement with the detent F, and its rear end arranged directly beneath the lower arm of the mainspring.

Our invention is not limited to the exact construction and operation of the parts for holding the ejector in its normal position and controlling the operation of said ejector, and at Figs. 4 and 5 we have shown slightly-modified constructions of said invention. In Fig. 15 4 we have shown the ejector E¹⁰ as normally held out of engagement with a shoulder b^{10} on the barrel B¹⁰ by a spring e^{10} , which is engaged with a shoulder at the lower end of said ejector. In this figure the trip or connection G¹⁰ between the mainspring of the hammer C¹⁰ and said ejector is shown as extended forwardly beneath the ejector for slightly elevating the same as the hammer is tripped in the operation of firing a cartridge-shell. At Fig. 5 we have shown a spring e^{20} as engaged with the arm e^{21} of the ejector E²⁰ for holding said arm out of engagement with the shoulder b^{20} and a slightly-modified construction of trip or connection G²⁰ as interposed between the mainspring of the hammer C²⁰ and the ejector E²⁰ for elevating said ejector as the hammer is tripped.

As will now be readily understood by those skilled in the art upon reference to the foregoing description and the accompanying drawings, the operation of our invention is as follows: The ejector is normally held by the detent F out of its position assumed when about to be compressed preparatory to actuating the extractor to discharge the shell and remains in said position until the hammer C is fired. When the barrel B is dropped without releasing or lowering the hammer to fire the cartridge-shell, the rear arm of the ejector is held out of engagement with the face or shoulder b , and being engaged with the extractor-rod d causes a slight backward movement of the extractor D and the corresponding cartridge-shell for permitting the engagement of the cartridge-shell by the fingers. This movement of the extractor is, however, insufficient to discharge the shell engaged thereby. When the hammer C is released or lowered to fire the cartridge-shell, the trip or connection G forces the detent F from operative position, and the ejector automatically engages its rear arm with the face or shoulder b . When the barrel B is dropped with the ejector in this position, the face or shoulder b forces the rear arm e' of the ejector forwardly until the movement of said barrel is sufficient to disengage the face or shoulder b from said arm, whereupon the ejector forcibly engages the extractor-rod and operates the extractor to discharge the cartridge-shell. As the barrel is elevated to its normal position after the cartridge-shell

is discharged the face b' forces the rear arm of the ejector downwardly and the detent automatically engages the shoulder e^2 for holding said ejector in its normal position.

Having thus fully described our invention, what we claim as new, and desire to secure by Letters Patent, is—

1. In a breech-loading firearm, the combination with a barrel and a frame, each having an engaging shoulder or face, and a movable extractor; of an ejector having separated spring-arms for engaging said shoulders or faces, one of the arms being movable from engagement with its corresponding shoulder or face for actuating the extractor to discharge the shell, and means for preventing the ejector from actuating the extractor, substantially as and for the purpose described. 75

2. In a breech-loading firearm, the combination with a barrel, a frame, and a movable extractor; of an ejector consisting of a spring supported by the barrel and arranged to be compressed by the dropping of the barrel 90 and to actuate the extractor to discharge the shell, said spring-ejector being provided with an engaging shoulder, and a pivoted detent supported by the barrel and movable into engagement with the shoulder of the spring-ejector for preventing the ejector from actuating the extractor, substantially as and for the purpose set forth. 95

3. In a breech-loading firearm, the combination with a barrel and a frame, each having an engaging shoulder or face, and a movable extractor; of an ejector provided with an engaging shoulder and having separated spring-arms for engaging said shoulders or faces on the barrel and frame, one of the arms being 100 movable from engagement with its corresponding shoulder or face for actuating the extractor to discharge the shell, and a detent for 105 preventing the ejector from actuating the extractor, substantially as and for the purpose 110 described. 115

4. In a breech-loading firearm, the combination with a barrel and a frame, each having an engaging shoulder or face, and a movable 115 extractor; of an ejector supported by the barrel and provided with an engaging shoulder, said ejector having separated spring-arms for engaging the shoulders or faces of the frame and barrel, and one of said arms being 120 movable from engagement with its corresponding shoulder or face for actuating the extractor to discharge the shell, and a detent supported by the barrel and movable into engagement with the shoulder of the ejector 125 for preventing the ejector from actuating the extractor, substantially as and for the purpose specified. 130

5. In a breech-loading firearm, the combination with a barrel and a frame, each having an engaging shoulder or face, and a movable extractor; of an ejector having separated spring-arms at its upper end for engaging said shoulders or faces, one of the arms be-

ing movable from engagement with its corresponding shoulder or face for actuating the extractor to discharge the shell, and an arm or projection supported by the barrel beneath the lower end of the ejector for preventing undue movement of the ejector, substantially as and for the purpose described.

5 6. In a breech-loading firearm, the combination with a barrel, a frame, and a movable extractor; of an ejector consisting of a spring arranged to be compressed by the dropping of the barrel and to actuate the extractor to discharge the shell, means for preventing the ejector from actuating the extractor, and a trip for forcing said means from operative position, substantially as and for the purpose specified.

10 7. In a breech-loading firearm, the combination with a barrel and a frame, each having an engaging shoulder or face, and a movable extractor; of an ejector having separated spring-arms for engaging said shoulders or faces, one of the arms being movable from engagement with its corresponding shoulder or face for actuating the extractor to discharge the shell, means for preventing the ejector from actuating the extractor, and a trip for forcing said means from operative position, substantially as and for the purpose set forth.

15 8. In a breech-loading firearm, the combination with a barrel and a frame, each having an engaging shoulder or face, and a movable extractor; of an ejector provided with an engaging shoulder and having separated spring-arms for engaging said shoulders or faces of the barrel and frame, one of said arms being movable from engagement with its corresponding shoulder or face for actuating the

extractor to discharge the shell, a detent for engaging the shoulder of the ejector and preventing said ejector from actuating the extractor, and a rocking trip having its front end movable into engagement with the detent for forcing the same from its operative position, substantially as and for the purpose described.

20 9. In a breech-loading firearm, the combination with a barrel and a frame, each having an engaging shoulder or face, and a movable extractor, of an ejector supported by the barrel and provided with an engaging shoulder, said ejector having separated spring-arms for engaging the shoulders or faces of the barrel and frame, and one of said arms being movable from engagement with its corresponding shoulder or face for actuating the extractor to discharge the shell, a pivoted detent supported by the barrel and movable into engagement with the shoulder of the ejector for preventing the operation of said ejector, a spring for forcing the detent into operative position, and a rocking trip having its front end movable into engagement with the detent for forcing the same from its operative position, substantially as and for the purpose specified.

25 In testimony whereof we have hereunto signed our names, in the presence of two attesting witnesses, at Ithaca, in the county of Tompkins, in the State of New York, this 15th day of September, 1896.
